(57) **CLAIM**

The ornamental design for a waste receptacle, as shown and described.

DESCRIPTION

FIG. 1 is a front perspective view of a waste receptacle showing our new design;

FIG. 2 is another front perspective view of the waste receptacle shown in FIG. 1;

FIG. 3 is another front perspective view of the waste receptacle shown in FIG. 1;

FIG. 4 is a front view of the waste receptacle shown in FIG. 1;

FIG. 5 is a rear view of the waste receptacle shown in FIG. 1;

FIG. 6 is a left side view of the waste receptacle shown in FIG. 1;

FIG. 7 is a right side view of the waste receptacle shown in FIG. 1;

FIG. 8 is a top view of the waste receptacle shown in FIG. 1; and,

FIG. 9 is a bottom view of the waste receptacle shown in FIG. 1.

The rectangular area on the top of the lid being shown in broken lines is to show environment only and form no part of the claimed design.
